US00D881943S

(12) **United States Design Patent** (10) **Patent No.:** **US D881,943 S**
Lee et al. (45) **Date of Patent:** **** Apr. 21, 2020**

(54) **DISPLAY SCREEN OR PORTION THEREOF
WITH GRAPHICAL USER INTERFACE**

(71) Applicant: **Samsung Electronics Co., Ltd.**, Suwon-si (KR)

(72) Inventors: **Heon Woo Lee**, Seoul (KR); **Miyeon Park**, Seongnam-si (KR); **Yongman Park**, Yongin-si (KR); **Jakyung Lee**, Seoul (KR); **Hyerim Kwak**, Seoul (KR); **Soyoung Lee**, Seoul (KR)

(73) Assignee: **SAMSUNG ELECTRONICS CO., LTD.**, Suwon-si (KR)

(**) Term: **15 Years**

(21) Appl. No.: **29/710,124**

(22) Filed: **Oct. 21, 2019**

CPC ... B60K 37/00; G06F 3/0481; G06F 3/04845; G06F 3/04817; G06F 17/212; G06F 19/3406; G06T 13/80; G06T 15/02

CLAIM

The ornamental design for a display screen or portion thereof with graphical user interface, as shown and described.

DESCRIPTION

The FIGURE is a front view of a display screen or portion thereof with graphical user interface showing our new design.

The broken lines at the outer perimeter of the FIGURE depict a display screen or portion thereof and form no part of the claimed design. The remaining broken lines in the
